UNITED STATES PATENT OFFICE.

EDWARD FELTMAN, OF OTTAWA, OHIO.

VERTICALLY-ADJUSTABLE SWINGING GATE.

1,177,094.

Specification of Letters Patent. Patented Mar. 28, 1916.

Application filed February 6, 1915. Serial No. 6,646.

To all whom it may concern:

Be it known that I, EDWARD FELTMAN, a citizen of the United States, residing at Ottawa, in the county of Putnam and State 5 of Ohio, have invented certain new and useful Improvements in Vertically-Adjustable Swinging Gates, of which the following is a specification.

This invention relates to improvements in 10 gates and more specifically to vertically-adjustable swinging gates.

The object of my invention is to provide a swinging gate that is vertically-adjustable, by means of a semicylindrical hinge member 15 provided with vertically disposed recesses adapted to receive a transversely disposed pin rigidly connected to the gate.

A further object of my invention is to provide a gate with a vertical adjusting attachment 20 so constructed that the entire gate may be readily raised in order to pass over any obstruction in its path, such as snow and ice.

Other objects of this invention not at this 25 time more particularly enumerated, will be clearly understood from the detailed description and drawings forming a part of this specification.

Furthermore, this invention consists in 30 the novel arrangement and combination of parts more particularly described in the following specification and embodied in the claim appended hereunto and forming a part of a part of this application.

35 Referring now to the drawings, which are merely illustrative of my invention, Figure 1 is a front elevation of a gate with my invention applied thereto. Fig. 2 is a detail horizontal sectional view of my improved 40 adjusting attachment, taken on the line 2—2 of Fig. 1. Fig. 3 is a detail vertical sectional view of my adjustment taken on the line 3—3 of Fig. 4. Fig. 4 is a detail transverse sectional view taken on the line 4—4 45 of Fig. 3.

Referring further to the drawings, wherein similar reference characters designate similar parts throughout the respective views, 1 designates a gate of any approved 50 construction. A metallic strip 2 is secured diagonally from a certain point near the top of the hinged end of said gate to the opposite lower end thereof. An L-shaped metallic strip 3 is mounted on said gate near the 55 hinged end thereof so that the longer arm

4 thereof is vertically disposed thereon while the shorter arm 5 is secured near the top thereof. The said arm 5 of said L-shaped member terminates in a swivel end 6 slidably mounted on a U-shaped hinge member 60 7, said U-shaped member being secured to a post 8. At the lower hinged end of said gate 1 is secured a U-shaped member 9, adapted to be secured to the gate 1, the base end of said member 9 extending outwardly 65 from said gate and carrying transversely thereof a cylindrical pin 10. A tongue 11 is formed integral with and in continuation of said member 9, the end of said tongue formed with a vertical split so as to provide 70 outwardly extending ears 12.

A semicylindrical hinge member generally designated by 13, is formed with a vertical slot 14 through the center thereof and a plurality of recesses 15 spaced apart 75 in the edges thereof, the recesses in one edge being diametrically opposite the recesses in the opposite edge. A ball shaped head 16 is secured to both ends of said hinge member, said heads being adapted to seat pivotally 80 in corresponding sockets 17 at the outer end of supporting members 18, said members 18 adapted to be secured to the post 8.

The tongue 11 of said U-shaped member 10 is adapted to fit slidably within the slot 85 14 of hinge member 13. The outwardly extending ears 12 are designed to prevent the tongue from being entirely removed from the slot. The transversely disposed pin is adapted to seat within any oppositely disposed two of the recesses 15. It will further be seen that when the forward end of the gate is raised, the pin 10 will disengage 90 from its recessed seat and may be readily reseated in any pair of the recesses to raise 95 or lower the gate as desired. It will also be seen that the gate pivots on the members 13 and 7.

The utility, adaptability, and advantages 100 of my improved form of vertically-adjustable swinging gates being obvious, it is unnecessary to further enlarge upon the same herein.

Having now described and pointed out the new and useful features of my invention, I do not limit myself to the shape of 105 certain parts where the shape is not essential, nor do I restrict myself to the exact details of construction shown and described, but mean and intend to claim all equivalents 110

and variations thereof not departing in principle from my invention and falling within the purview of the appended claim.

What I claim as my invention and desire to secure by Letters Patent is:

The combination with a gate, of a mounting therefor, including a post, a U-shaped member secured to the post, a gate swivel slidably mounted upon said member, laterally extending spaced supports mounted adjacent the bottom of the post, sockets formed on the free ends of the supports, a semi-cylindrical member, ball shaped heads projecting from opposite ends of the semi-cylindrical member for engagement with the sockets for swivelly mounting the semi-cylindrical member, said semi-cylindrical member being provided with a central and longitudinally extending slot and with a plurality of uniformly spaced and oppositely

disposed recesses in its free edges, a U-shaped member carried by the gate, a tongue projecting from the U-shaped member and slidably arranged in the slot, a pin transfixing said tongue and coacting with the recesses for removably holding the tongue in various adjusted positions to consequently control the adjustment of the gate, and oppositely extending ears formed by slitting and bending the free end of the tongue for preventing the withdrawal of the tongue from the semi-cylindrical member, yet permitting of the withdrawal of said pin from said recesses when adjusting the gate. 25 30 35

In testimony whereof I affix my signature in the presence of two witnesses.

EDWARD FELTMAN.
